(57) **CLAIM**

The ornamental design for a dump truck body panel, as shown and described.

DESCRIPTION

FIG. 1 is a perspective view of a dump truck body panel embodying my design;

FIG. 2 is a top view of the dump truck body panel;

FIG. 3 is a right side view of the dump truck body panel;

FIG. 4 is a back view of the dump truck body panel;

FIG. 5 is a front view of the dump truck body panel;

FIG. 6 is a bottom view of the dump truck body panel; and,

FIG. 7 is a left side view of the dump truck body panel.

The broken lines shown throughout the drawing views are for illustrative purposes only and form no part of the claimed design.
